UNITED STATES PATENT OFFICE.

MANLEY HOWE AND D. FRANK HARTFORD, OF BOSTON, MASSACHUSETTS.

MECHANISM FOR DRIVING VELOCIPEDES.

Specification forming part of Letters Patent No. 87,259, dated February 23, 1869.

To all whom it may concern:

Be it known that we, MANLEY HOWE and D. FRANK HARTFORD, of Boston, in the county of Suffolk and State of Massachusetts, have invented certain Improvements in Velocipedes, of which the following is a full, clear, and exact description, reference being had to the accompanying drawings, making part of this specification, in which—

Figure 1 is a plan of a portion of a velocipede having our improvement applied thereto. Fig. 2 is a longitudinal section on the line $x x$ of Fig. 1. Fig. 3 is a longitudinal section on the line $y y$ of Fig. 1. Fig. 4 is a transverse section on the line $z z$ of Fig. 1. Fig. 5, detail, enlarged.

In the ordinary velocipedes, as now constructed, which are propelled by means of foot-crank, only a limited average can be obtained, as the length or throw of the cranks must be within the range of action of the feet or limbs of the rider.

To enable other skilled in the art to understand and use our invention, we will proceed to describe the manner in which we have carried it out.

In the said drawings, A represents the driving shaft or axle of a velocipede, the wheels of which are intended to be secured at $a b$, the shaft being supported in a frame, B, merely for convenience in illustrating our invention. This shaft A is revolved by the feet of the rider in the following manner: C is a hollow wheel or pulley, which is fitted so as to turn loosely upon the shaft A, and is provided with a rectangular groove, c, for the reception of a strong leather strap or band, d, which extends partially around the pulley, one extremity being secured to it by a screw, e, while its opposite end passes between a rod, f, and a roll, g, and has attached to it a stirrup, h, which is intended to be moved up and down between the bars $i j$ of an inclined frame, D, and is so placed as to be in a convenient position to receive the foot of the rider, who sits upon a seat above. (Not shown in the drawings.) Within the pulley C is pivoted a pawl, k, which engages with the teeth of a ratchet, l, secured to or forming a part of the shaft A, a spring, m, serving to keep the pawl in contact with the teeth of the ratchet, and thus, as the stir-

rup h is forced down by the foot in the direction of the arrow 7, the pulley C is partially revolved by the strap d, and its motion communicated, through the pawl k and ratchet l, to the driving shaft or axle A, which is thus rotated as required. As soon, however, as the pressure of the foot is removed from the stirrup h the pulley C is revolved in the opposite direction by a flat coiled spring, n, one end of which is secured to the hub 8 of the pulley, and the opposite end to a rod, 9, and the stirrup h is thus returned to its original position, ready to be again forced down by the foot, the pawl k passing freely over the teeth of the ratchet l as the pulley is carried back by the spring.

Instead of a coiled spring, n, a short chain may be attached to the hub 8 and wound partially around it, one end of the chain being secured to a flat or spiral spring attached to the frame-work.

The hub 8 is attached to a circular plate, E, secured to and forming one side of the pulley C, which is prevented from moving laterally upon the shaft A by the ratchet l, one side of which bears against the inner face of the pulley and the opposite side against the plate E.

The pawl k may be held out of contact with the teeth of the ratchet l, so as to allow the velocipede to be moved backward by hand, by a pin or stop, o, the inner end of which is inclined and passes through the side of the pulley C, being forced in beneath the pawl, so as to raise it out of contact with the teeth of the ratchet, by a spring, p, the outer end of which is forked and fits into a groove at the end of the pin o. This pin is held, when drawn out into the position seen in Fig. 1, by a small projection, 10, on its side, which rests against the face of the pulley; and when the pin is turned so as to bring the projection 10 in line with an opening, 11, Fig. 5, in the side of the pulley, it is forced in by the spring p, and the pawl k held up as required. Two of these pulleys C are intended to be secured to the shaft A, each provided with a strap and stirrup, as above described, one for each foot, so that they may be operated alternately to produce a continuous rotary motion of the shaft or axle of the velocipede.

In the drawings, however, the two pulleys

are of different construction, the pulley G and mechanism connected therewith being constructed according to a modification of our invention, which we will now describe.

The wheel or pulley G is securely fastened upon the shaft A by means of a set-screw, q', and is provided with a rectangular groove, r, in which is fitted a chain, H, one extremity of which is secured to a spiral spring, s, attached to the frame-work, while the opposite end is secured to a stirrup, I, which slides in ways or grooves in the inclined frame D, and is so placed as to be in a convenient position to receive the foot of the rider.

The periphery of the pulley G on each side of the groove r is provided with ratchet-teeth t, into which fit two pawls, u, pivoted to the chain H, one on each side, and kept in contact with the teeth by springs 12; and thus, as the stirrup I is forced down in the direction of the arrow 14 by the foot of the rider, the chain H, with its pawls, will partially revolve the pulley G and driving-shaft A, while as soon as the pressure of the foot is removed from the stirrup the spring s will draw the chain back over the pulley, without moving the latter, (the pawls u riding over the ratchet-teeth t,) bringing the stirrup into the position seen in Fig. 1, ready to be again forced down by the foot of the rider.

If it should be desired to move the velocipede backward by hand, it is merely necessary to draw the chain H sufficiently far forward to carry the pawls u out of contact with the ratchet-teeth t; or the pawls may be raised and held up by any suitable device.

It is evident that in practice it would be found desirable to have the two pulleys upon the shaft A of the same construction, either similar to C or G, for the sake of uniformity; but the velocipede could be operated equally as well if two pulleys of different construction were employed, as above described.

It will be seen that the power is applied to the peripheries of both pulleys C and G, and that by increasing the diameter of the pulleys the leverage may be increased without neces-

sitating any increase in the length of the stroke of stirrups, to a point much beyond that which can be attained by the use of cranks, as the length of the latter must be limited within the range of action of the limbs of the rider.

Furthermore, in our improved velocipede the same leverage or power is exerted whether the stroke of the stirrups is long or short, thus adapting it for persons with limbs of various lengths.

It is evident that the straps or chains d H, instead of being attached to stirrups for the reception of the feet, may be arranged so as to be operated by the hands without departing from the spirit of our invention; and instead of springs n or s being employed to return the pulleys and stirrups to their normal positions, the pulleys may be so connected together, by a cord, chain, or other device, that the revolution of one will rotate the other in the opposite direction, and thus as one stirrup is forced down the other will be drawn up. We prefer, however, to use the springs, as the pulleys are then entirely independent of each other.

What we claim as our invention, and desire to secure by Letters Patent, is—

1. The combination, with a velocipede, of a ratchet and reciprocating pawl, and mechanism for disengaging the pawl from the ratchet, so that the velocipede may run backward, substantially as described.

2. The combination, with the wheel-supporting axle of a velocipede, of a fixed ratchet-drum and a reciprocating pawl-carrying chain, all operating together, substantially as described.

3. The combination, with the chain or equivalent operating the ratchet-drum or its equivalent, of the stirrup working in guide-ways, substantially as described.

MANLEY HOWE.

D. FRANK HARTFORD.
